LAMP FINIAL

Paul Chilo, Chicago, Ill.

Application August 28, 1935, Serial No. 38,236

6 Claims. (Cl. 41—10)

My invention relates to lamp finials and similar devices.

My invention relates more particularly to improvements in the construction of lamp finials, especially with regard to novelty and attractiveness of the same.

An object of my invention is to provide an improved and attractive finial that is easily and cheaply manufactured and capable of long use without becoming broken or out of order.

A further object is to provide an improved construction of lamp finial having a decorative object removably secured thereto.

A further object is to provide an improved lamp finial having a plurality of spring elements capable of supporting a decorative and attractive display member therein.

A further object is to provide an improved lamp finial constructed of a plurality of individual units removably secured together so that different elements may be assembled together for different types or colors of lamp shades.

Other objects and advantages will be more apparent from the following description wherein reference is had to the accompanying sheet of drawing, upon which,

Fig. 1 is a front perspective view of a lamp and lamp shade assembly showing my improved finial in position thereon;

Fig. 2 is a vertical sectional view thereof taken generally on the line 2—2 of Fig. 1;

Fig. 3 is a side elevational view of my improved finial showing a cap member mounted thereon;

Fig. 4 is a view of the cap member showing the spring mounting element thereof in section;

Fig. 5 is a side elevational view of a modified form of finial with portions thereof in section and

Fig. 6 is a side elevational view of the finial shown in Fig. 5.

In Fig. 1 I have illustrated a typical lamp assembly comprising the upper portion of the lamp stand 10 with the shade 12 and an inverted reflector member 14 mounted thereon. The lamp shade is ordinarily provided with a central support member 16 from which a plurality of radially extending arms 18 connect to the upper rim 20 of the lamp shade. The support member 16 is usually fastened to a vertical post upon the upper end of the lamp harp in lamps which do not have inverted reflectors.

Where an inverted reflector is used, however, the lamp finial 22 is adapted to be secured to the supporting member 16 by means of a screw member 24 that extends through a central opening 26 in the member 16 and screw-threadedly engages

in a suitably tapped opening 28 in the finial 22. The finial 22 may be provided with a shank member 30 having any desirable exterior appearance and being provided at its upper end with a shoulder 32 upon which a spring retainer member 34 is adapted to be mounted. The retainer member 34 is secured in position by being riveted or otherwise fixedly attached to the upper end of the shank 30.

The member 34 may be provided with a plurality of arcuately shaped finger members 36 adapted to form a semi-spherical pocket within which a ball member 38 is adapted to be positioned. The ball member 38 may have a larger diameter than the sides of the pocket so that when the same is mounted in position it is yieldingly held by the spring fingers 36. It will be noted that the fingers extend beyond the center of the ball member 38. The ball member 38 is preferably formed of glass or other transparent material so that the same will add greatly to the attractiveness of the lamp assembly, especially when mounted in connection with an inverted reflector such as I have shown. Under these conditions light rays will be reflected from the transparent ball member 38, adding greatly to the attractiveness of the lamp assembly. The ball members are provided in a plurality of colors so that for example, with a red shade a red ball may be provided and with a green or yellow shade similar or different color combinations may be secured.

In Figs. 3 and 4 I have illustrated a cap member 40 of any suitable or desirable shape which may be attached to the upper side of the ball member 38. The cap member 40 is provided with a spring member 42 similar to the spring member 34 and provided with a plurality of fingers 44. Thus the cap member may be yieldingly mounted upon the finial if desired and it may easily be removed for cleaning or other purposes.

In Figs. 5 and 6 I have illustrated a modified form of lamp finial in which I provide the shank member 30 and a spring member 46 secured to the top thereof as hereinbefore described. This spring member, however, may be formed with a pair of socket portions 48 and 50 suitably connected by a spring strap member 52 so that a ball member 54 may be resiliently held between the socket members 48 and 50. A suitable cap member 40 may be mounted upon the upper socket 50 as hereinbefore described.

From the foregoing it will be obvious that a unique and highly attractive lamp finial has been provided. With either of the forms shown it

will be obvious that a ball member of any desired size can be mounted in and form part of the finial, the size of the ball depending necessarily upon the size of the pocket formed by the spring members.

Many and various modifications may be made in the exact details shown without departing from the spirit of the invention. While I have illustrated and described a specific embodiment 10 of my invention, I do not wish to be limited to the exact details shown; rather what I desire to secure and protect by Letters Patent of the United States is:

1. A lamp finial comprising a shank member 15 having an axial tapped opening extending into the lower end thereof, a spring member secured to the upper end of said shank member, said spring member having a plurality of spring fingers and a ball member yieldingly held above 20 said shank member by said fingers.

2. A lamp finial comprising a shank member having an axial tapped opening extending into the lower end thereof, a shoulder upon the upper end thereof, a spring member secured on said 25 shoulder, said spring member having a plurality of fingers thereon and a ball member yieldingly held above said shank member by said fingers.

3. A lamp finial comprising a shank member screw-threadedly mounted axially over a lamp 30 shade, a spring holder member secured to the upper end of said shank member, a spherical member resiliently held in said spring member

and a cap member resiliently held on the upper side of said spherical member.

4. A lamp finial comprising a shank member screw-threadedly mounted axially over a lamp shade, a spring holder member secured to the 5 upper end of said shank member, said member having a plurality of fingers, a spherical member resiliently held in said fingers and a cap member resiliently held on the upper side of said spherical member.

5. A lamp finial comprising a cylindrical shank member having an axial tapped opening in its lower end, a shoulder on its upper end, a spring member having a central opening riveted to said shank member and resting on said shoulder, said 15 spring member having a plurality of arcuately shaped arms to form a semi-spherical pocket and a ball member having a larger diameter than said pocket yieldingly held therein by said arms.

6. A lamp finial comprising a cylindrical shank 20 member having an axial tapped opening in its lower end, a shoulder on its upper end, a spring member having a central opening riveted to said shank member and resting on said shoulder, said spring member having a plurality of arcuately 25 shaped arms to form a semi-spherical pocket, a ball member having a larger diameter than said pocket yieldingly held therein by said arms and a cap member mounted on said ball member, said 30 cap member having a plurality of arcuately shaped spring arm members.

PAUL CHILO.
